UNITED STATES PATENT OFFICE

106,553

DESIGN FOR A CHAIR

Ivey Wetherington, Grand Rapids, Mich.

Application August 19, 1937, Serial No. 71,202

Term of patent 3½ years

To all whom it may concern:

Be it known that I, Ivey Wetherington, a citizen of the United States, residing at Grand Rapids, in the county of Kent and State of Michigan, have invented a new, original, and ornamental Design for a Chair, of which the following is a specification, reference being had to the accompanying drawing, forming a part thereof, in which:—

The figure is a perspective view of a chair showing my new design.

I claim:

The ornamental design for a chair substantially as shown,

IVEY WETHERINGTON.
